David G. Hills, Hartford, Conn., assignor to Plax Corporation, West Hartford, Conn., a corporation of Delaware

Application February 23, 1954, Serial No. 29,155

Term of patent 14 years

(Cl. D58—25)

To all whom it may concern:

Be it known that I, David G. Hills, a citizen of the United States, resident of Hartford, county of Hartford, State of Connecticut, have invented a new, original, and ornamental Design for a Bottle, of which the following is a specification, reference being had to the accompanying drawing, forming a part hereof.

Fig. 1 is a top plan view of a bottle showing my new design;

Fig. 2 is a side elevational view of the bottle;

Fig. 3 is a rear elevational view of the bottle; and

Fig. 4 is a perspective view of the bottle taken on a reduced scale.

I claim:

The ornamental design for a bottle, substantially as shown.
